T. WILSON.
DRUM ATTACHMENT.
APPLICATION FILED DEC. 11, 1920.

1,413,445.

Patented Apr. 18, 1922.

Inventor:
Tom Wilson

By Foree Bain & Hinkle Atty.

UNITED STATES PATENT OFFICE.

TOM WILSON, OF CHICAGO, ILLINOIS, ASSIGNOR TO WILSON BROS. MFG. COMPANY, A CORPORATION OF ILLINOIS.

DRUM ATTACHMENT.

1,413,445.

Specification of Letters Patent. Patented Apr. 18, 1922.

Application filed December 11, 1920. Serial No. 429,913.

To all whom it may concern:

Be it known that I, TOM WILSON, a citizen of the United States, residing at Chicago, in the county of Cook and State of Illinois, have invented certain new and useful Improvements in Drum Attachments, of which the following is a specification.

This invention relates to drum attachments.

10 It relates more particularly to combined snare strainers and mufflers.

One of the objects of the invention is to provide an improved snare strainer and muffler.

15 Another object is to provide a snare strainer and muffler which may be readily adapted to suit the convenience of the drummer.

Another object is to provide a snare 20 strainer and muffler having a plurality of operative positions.

Another object is to provide a snare strainer and muffler whose operating lever 25 may be brought close to the shell of the drum so as not to interfere with an enclosing case.

A further object is to provide a strainer and muffler which is simple in construction, reliable in operation, easy to apply and inexpensive to manufacture and assemble.

30 Other objects will hereinafter appear.

An embodiment of the invention, applied to a drum in two different ways, is illustrated in the accompanying drawing.

The views in the drawing are as follows:—

Fig. 1 is a front elevation of a portion of a snare drum, equipped with a combined snare strainer and muffler mounted on a hoop thereof.

40 Fig. 2 is a top plan of the snare strainer and muffler, showing the different positions the operating lever may assume when the snares are relaxed.

Fig. 3 is a top plan, showing the different 45 positions the operating lever may assume when the snares are tensioned.

Fig. 4 is a separated perspective of the strainer and muffler.

Fig. 5 is a front elevation of the strainer 50 and muffler mounted on the shell of a drum, and

Fig. 6 is a side elevation thereof.

The drum comprises, in general, a cylindrical shell 1, which may be of wood or

metal, and two heads of flesh. Ordinarily 55 each head is stretched upon and secured to a hoop 2, commonly called a "flesh hoop." The flesh hoops and, consequently the heads, are held in place by tension hoops 3. The head tension hoops may be made of metal or 60 wood as desired. Suitable means, such as independent screw operated head tensioning rods 4, are usually provided, whereby the tension of the heads on the opposite ends of the drum may be separately and inde- 65 pendently adjusted at will.

Snare drums are provided with snare strings which, when in use, lie against one of the heads of the drum. When the snare effect is not desired, the snare strings and 70 head are separated. One end of all of the snares is anchored, by suitable means not shown, to the drum. The other end of the snares is secured to the combined strainer and muffler. Usually the snare strings pass 75 through holes or slots in the tension hoops.

The strainer and muffler has a base or supporting base plate 5 secured, adjacent one end, to the head tension hoop 3 on the snare end of the drum by suitable means, such as 80 screws 6. Base plate 5 is provided, at its opposite end, with an outwardly extending lug or bracket 7. The upper surface of bracket 7 has a square boss 8 thereon. A hole 9 extends through the bracket at the 85 center of boss 8. The bracket is also provided with a slot 10 through which the snare strings may be passed.

Slidably fitting in hole 9 is a rod or plunger 11 externally threaded on its upper end 90 to receive a tension adjusting thumb nut 12. The other end of rod 11 is reduced in diameter to provide an annular shoulder 13 and is interiorly threaded to receive a screw 14.

95 The snares are held in a snare clamp comprising a pair of screw coupled plates 15 and 16. Plate 15 is provided with a perforated ear or lug 17 which fits over the reduced end of rod 11 and is clamped firmly against the 100 shoulder thereof by screw 14.

Between nut 12 and bracket 7 and loosely encircling plunger 11 is a collar 18. Collar 18 has a pair of pins or lugs 19 projecting from opposite sides of its circumference and 105 upon these pins an operating lever 20 is pivotally mounted. The sides of the bifurcated lower end of lever 20 are spaced apart

to loosely fit down upon the sides of the square boss 8 on the top of bracket 7 and, when so fitted, prevent the lever and its supporting collar 18 from being rotated about plunger 11. The lower end of lever 20 is cam-shaped to cooperate with the upper surface of bracket 7. This cam is so formed that when the lever is depressed as shown by the full lines in Fig. 1 and in Fig. 3, 10 collar 18 is forced against nut 12, which acts as an abutment, and the plunger is moved upwardly to tension the snares. When the lever is elevated, as shown by the dotted lines in Fig. 1 and in Figs. 2 and 4, the cam allows a spring 21, which surrounds plunger 11 between ear 17 and bracket 7, and the snares to force plunger 11 downwardly until the snare tension has been sufficiently relaxed to muffle the drum. The point or elevated portion 22 of the cam passes beyond the plane through pins 19 and the axis of plunger 11 when the operating lever is near its string tensioning or string relaxing position. Thus the muffler is self retaining in 15 either position. When the drummer wishes to muffle the drum it is necessary to move the operating lever only a portion of its travel because, as soon as the elevated portion of the cam passes beyond the plane 20 through the lever pivots and the axis of the plunger, the force of spring 21 and the snares snap the lever to its extreme position wherein the string tension is completely relaxed and the drum is muffled.

25 The necessary tension of the snare strings for the desired snare effect can be secured by turning the operating lever to tensioning position (see Fig. 3) and turning adjusting nut 12 to relieve or increase the tension.

30 After the desired tension is obtained, the drum may be muffled by throwing the operating lever to tension relaxing position (see Fig. 2). The snare strings, however, may be instantly returned to effective position at the 35 adjusted tension by simply manipulating the operating lever.

The operating lever may be moved in different planes to any one of three positions to tension the snares. In each movement 40 the boss on the bracket acts as a guide, cooperating with the bifurcated end of the operating lever, to properly locate the lever for operation. When the lever is in snare relaxed position, the drummer turns the lever and supporting collar about the axis of the 45 plunger until the lever is in the most convenient position and then, by rocking the lever about its pivot, tensions the snares against the head of the drum. The three 50 snare tensioning positions of the lever are shown in Fig. 3 and the corresponding lever positions for relaxed snares are shown in Fig. 2. The snare strainer and muffler thus may be readily adapted to suit the convenience and needs

of the drummer. After a little experience the drummer will find which position is best adapted for his use and thereafter the co-operating sides on the boss of the bracket and the operating lever will hold the lever 55 to the desired plane of movement.

In case it is desired to fit the drum snugly into a case the operating lever, in snare relaxed position, may be turned inwardly toward the shell of the drum, as shown in 75 Fig. 2.

The muffler and strainer may be readily assembled and taken apart. If the lever becomes broken or bent it may be removed by simply unscrewing nut 12 and lifting 80 off the collar and lever, the rest of the structure remains intact. Should it become necessary to replace the spring it is only necessary to remove screw 14. The snares are retained in the clamp and the remainder 85 of the structure remains intact. The new spring having been slipped upon the plunger, the muffler is restored to its original condition and adjusted tension by replacing the snare clamp and screw 14. 90

Figs. 5 and 6 show a combined snare strainer and muffler, having the same characteristics and operation as those previously described, secured to the shell of the drum. The base plate 25 may be made shorter 95 since it does not extend to the hoop and no snare slot is required. The base plate is attached to the shell by a suitable support or bracket 26.

Having described my invention what I 100 claim as new and desire to secure by Letters Patent, is:—

1. A combined snare strainer and muffler comprising a base for rigid attachment to a drum, a bracket projecting from the base 105 and provided with an opening therethrough, a plunger slidably fitting in the opening in the bracket, a tension adjusting nut on the plunger, a collar loosely surrounding the plunger between the bracket and the nut, 110 a cam lever pivoted to the collar and co-operating with the bracket and nut to slide the plunger through the opening in the bracket, a snare clamp carried by the plunger, and a spring surrounding the 115 plunger between the snare clamp and bracket.

2. A combined snare strainer and muffler comprising a base for rigid attachment to a drum, a snare clamp for holding one end of the snares, a plunger to which the snare clamp 120 is secured, a bracket projecting from the base and provided with an opening in which the plunger slidably fits, a collar surrounding and slideable upon the plunger, a cam lever pivoted to the collar and co-operating with the bracket to move the collar, and an abutment on the plunger in the path of the collar and through which the operation of the cam lever slides the plunger through the bracket. 125

3. A combined snare strainer and muffler 130

comprising a base for attachment to a drum, a movable snare clamp carried by the base, an operating lever cooperating with the base and snare clamp to tension and relax all of 5 the snares simultaneously, and a loose connection between the base and lever for giving said lever a plurality of planes of movement in tensioning and relaxing the snares.

4. The combination of a drum, snares 10 therefor, a snare clamp for holding one end of the snares, a plunger to which the snare clamp is secured, a base for attachment to the drum and having a bracket with an opening for the plunger and through which 15 the plunger may reciprocate, snare tension adjusting means on the plunger, and an operating lever loosely carried on the plunger and operable in a plurality of planes to reciprocate the plunger and tension and relax 20 all of the snares simultaneously.

5. A drum muffler and snare strainer comprising a base for attachment to a drum, a bracket projecting from the base and having an opening therethrough, a plunger slidably fitting in the opening in the bracket, a cam lever pivotally and rotatably mounted relative to the plunger to be operated in a plurality of planes, a guide on the bracket and cooperating with the cam lever to temporarily retain the same in any of its operative planes, and adjustable means cooperating with the plunger and the cam lever 25 30

to communicate the movement of the cam lever to the plunger.

6. A combined snare strainer and muffler 35 comprising a snare clamp, a plunger carrying the clamp, a base for attachment to a drum, a bracket projecting from the base and having an opening in which the plunger 40 slidably fits, a collar movably fitted on the plunger, a cam lever pivoted to the collar and cooperating with the bracket to move the collar, a guide on the bracket and cooperating with the cam lever to hold the same in any one of a plurality of operative planes, 45 an adjustable abutment on the plunger and through which movement of the collar is communicated to the plunger, and a spring for retaining the abutment in engagement 50 with the collar.

7. A combined snare strainer and muffler having a base for attachment to a drum, a movable member for holding a snare string, a lever for moving said member and thereby tension and relax the snare string, and means 55 cooperating with the lever and said member to allow the lever to be moved to a plurality of positions providing equal relaxation of the snare and to a plurality of positions providing equal tension of the snare. 60

In testimony whereof I hereunto subscribe my name.

TOM WILSON.
